UNITED STATES PATENT OFFICE.

CHARLES BATEMAN AND WILLIAM H. LYDA, OF GALES CREEK, OREGON;
SAID LYDA ASSIGNOR OF ONE-HALF OF HIS RIGHT TO BRICE WILSON,
OF FOREST GROVE, OREGON.

LOG-LOADING ATTACHMENT FOR SKIDWAYS.

SPECIFICATION forming part of Letters Patent No. 556,571, dated March 17, 1896.

Application filed February 28, 1893. Serial No. 463,447. (No model.)

To all whom it may concern:

Be it known that we, CHARLES BATEMAN and WILLIAM H. LYDA, citizens of the United States, residing at Gales Creek, Washington county, and State of Oregon, have invented a certain new and useful Log-Loading Attachment for Skidways, of which the following is a specification, reference being had to the accompanying drawings as a part hereof.

Our invention relates to mechanical contrivances designed to be used in place of the ordinary blocks to slip or load the logs after having been turned off the skidways or platform onto the carriage conveying the same to the saw. It is our object to combine such contrivance with the usual stationary skidways on the platform, and to place the operating of the same under the control of the sawyer, so as to economize labor. To carry our invention into effect we provide said stationary skidways with adjustable skids, adapted to be thrown at a steep incline and returned back in place, as illustrated in the accompanying drawings above referred to, and hereinafter described.

In the drawings, Figure 1 is a detail of an attachment to prevent injury to the skids; Fig. 2, a perspective view of skidways or platform with our invention attached, a portion of the carriage being also shown so as to make the illustration more comprehensive. Fig. 3 is a sectional side elevation on lines xx , Fig. 2, showing the platform, a portion of the housing for the adjustable skids, and the mechanism for operating same. Fig. 4 is a bottom view of an adjustable skid, the housing therefor, and stationary skidways; and Figs. 5 and 6 are details of construction.

The letters designate the respective parts of our invention referred to.

Two of our log-loading attachments are used ordinarily, but for heavy logs it may become necessary to use more.

The construction of our invention is as follows: The skids A, which may be made of wood or iron, as deemed preferable, are supported at one end on cams a' , pivoted on their journals a^3 in the housing b of said skids, and the other ends of the skids are supported on lifting-arms c (see Fig. 5) fixed on a shaft d ,

extending horizontally through the platform on which the skidways are mounted to the reach of the sawyer, so that by operating the said shaft d the lifting-arms may be raised and lowered again. The cams a' and lifting-arms c are connected with each other by means of the rods e , provided with turnbuckles e' , the ends of said rods being respectively attached to the ears a^2 on the cams and to the ears c' on the lifting-arms c , thus the position and throw of the cam may be adjusted as required. The skids, as seen in Fig. 4, have longitudinal grooves g along their bottom edges adapted to permit the rods e to operate therein in rotating or throwing the cams a' . In the drawings such groove is shown as extended along the entire length of said bottom edges of the skids and the lifting-arms c , provided with tongues c^2 at their ends, adapted to be inserted in said grooves as such lifting-arms raise the skids to a cant. This last-described construction is optional, however, and the grooves and tongues had preferably be omitted when my invention is designed for very heavy work, to avoid having parts broken by lateral knocks. The said skids A and their operating mechanism are inclosed in housing b , as shown, which housing is fitted in the stationary skidways b' , so that the facings will be flush therewith. The springs f , (see Figs. 2, 3, and 6,) provided at the inner ends of said housing, press lightly against the ends of the skids, and are designed to keep out litter and dirt, which otherwise might get inside of such housing and interfere with the working of said skids. To facilitate the removing of cants we have provided the rollers g^0 , g' , and g^2 , (see Fig. 1,) supported in suitable bearings on the exterior of said housing, as shown in the drawings. The use of these rollers is optional, however, they being mainly intended to prevent wear of the skids by cants being pulled to and fro over them, as is usually the case in mills in which no pony-saw is used. The skids are also provided with rollers h at their inner corners to prevent the latter from mashing into the logs and holding the same in case a log should be thrown so far over as to fall on such corners.

In constructing our invention the parts

thereof should be so arranged and proportioned that when the skids A are placed at their steepest incline the outer ends thereof will project upward sufficiently to come a trifle 5 above the head-blocks on the carriage, and sufficiently outward to extend a trifle past the ends of the head-blocks, so that there will be no exposed corners to catch the logs when rolled on the carriage.

10 Having thus described our invention, what we claim is—

In a log-loading attachment for skidways, the combination of a platform, movable skids mounted crosswise of the same therein, housings for said skids in the platform, cams mounted in the housings, pivotally supporting the outer ends of said skids, a horizontal

operating-shaft mounted in the platform, at right angles to the skids, lifting-arms c, for supporting and raising the inner ends of the skids, rigidly secured on the operating-shaft, rods adjustable lengthwise connecting said cams with the lifting-arms to rotate the cams and operate the device, substantially as described and set forth. 20 25

In testimony whereof we have hereunto subscribed our names in the presence of two witnesses.

CHARLES BATEMAN.
WILLIAM H. LYDA.
